UNITED STATES PATENT OFFICE.

CHARLES F. WRIGHT, OF AKRON, OHIO, ASSIGNOR TO THE DIAMOND MATCH COMPANY,
OF CHICAGO, ILLINOIS, A CORPORATION OF ILLINOIS.

MACHINE FOR MAKING MATCHES FROM SHEET MATERIAL.

Application filed September 9, 1927. Serial No. 218,383.

This invention relates to machines for making matches, having reference more especially to mechanism for producing strips of match splints from sheet material, such as 5 pasteboard or veneer, my principal object being to provide simple and efficient means whereby such strips are rapidly and accurately produced.

The invention is especially, though not exclusively, designed for use in connection with or as an attachment to a match making machine of the general character illustrated in Letters Patent of the United States No. 636,170, dated October 31, 1899, wherein is 10 employed a suitable chain of strip holding devices operative to carry strips of splints to and through the dipping and other stations. This carrier is moved intermittently, and in each dwell thereof the leading end of a web 15 of match stock, of suitable width, is advanced by intermittently acting feed rolls into engagement with one of the strip holders. In each succeeding movement of the web it passes between complementary bar dies in the 20 vicinity of the carrier, which dies, in each pause of the web, are operative to slit the web longitudinally in parallel splint lines and at the same time offset or spread the alternate subdivisions to facilitate the 25 subsequent dipping operations. As each succeeding row of subdivisions is formed the web is severed transversely by a vertically reciprocating knife to produce a leading splint strip having an unslotted marginal portion which 30 is held in a holder of the carrier.

In the preferred form of embodiment of my invention herein illustrated, a revoluble cutting element for longitudinally slitting the web at spaced intervals throughout its length 35 is arranged between the web feeding means and the bar dies, the latter being utilized as a spreader for alternate splints formed by the longitudinally slitted portions of the web. This cutting element comprises a roll having its axis of rotation longitudinally of the direction of travel of the web and having peripheral blades parallel to said axis, in combination with means for effecting relative co-operative movement between the roll and the web, transversely of the latter, so that the blades consecutively incise the web throughout its width in parallel longitudinal lines. Means are provided to effect and ensure the proper registry or timing of the cutter roll

at each side of the web, preparatory to each 55 succeeding revolution of the roll, and the roll is also provided with means for severing the alternate slotted portions of the web at their trailing ends, which portions are subsequently spread from the normal plane of the web. 60

The invention also comprises novel features of construction and combinations of parts which will be hereinafter described, the scope of the invention then being defined in the appended claims. 65

In the drawings—

Figure 1 is a side elevation of a portion of a match making machine equipped with splint cutting mechanism embodying my invention, the sheet match stock being indicated. 70

Fig. 2 is an enlarged view of a portion of the mechanism shown in Fig. 1.

Fig. 3 is a plan of the mechanism illustrated in Fig. 1, the reciprocating splint 75 spreading and cutting devices being omitted to show the condition of the stock after it has been acted upon by the revoluble and reciprocating cutters.

Fig. 4 is a transverse vertical section 80 through the revoluble cutter and adjuncts, as on the line 4—4 of Fig. 3.

Fig. 5 is a longitudinal vertical section, partly in section, as on the line 5—5 of Fig. 3, but including the reciprocative splint 85 spreading and cutting devices.

Fig. 6 is a vertical section through the revoluble cutter and adjuncts, as on the line 6—6 of Fig. 4.

Fig. 7 is a vertical section at one end of the 90 revoluble cutter, as on the line 7—7 of Fig. 6, the serrated cutting disk being partly shown in elevation.

Referring to the drawings, 10 designates a suitable supporting frame, and 11 a power 95 driven shaft journaled in bearings in the frame.

12 designates a portion of an intermittently movable carrier adapted and arranged to receive strips of match splints and convey 100 them in spaced parallel relation through succeeding stations for paraffining, heading and drying. The form of carrier herein illustrated comprises an endless chain of recessed links provided at regular intervals with 105 spring clips, 13, which co-act with the adjacent walls of the recesses to afford regularly spaced card or strip holders, which carrier is

geared with and driven from a shaft 14 of the machine in any usual or approved manner.

15 designates a pair of parallel feed rolls spaced somewhat in front of the strip receiving portion of the carrier and adapted to engage a web of match stock, as S, and to advance the web intermittently toward the carrier. The shafts 16 of these rolls have their bearings in suitably disposed boxes on the main frame, and one of the shafts has fast thereon a ratchet 17 with which engages a pawl 18 carried by a crank disk 19 loose on such shaft. This disk is operatively connected by means of a rod 20 with a crank 21 on the shaft 11, and hence the feed rolls are intermittently rotated in the usual manner.

Fastened on the main frame, in rear of the feed rolls, is a horizontal table 22 upon which is supported a plate 23 whereof the upper surface is in horizontal alignment with the bite of the feed rolls and is adapted to receive and support each succeeding portion of the web which is advanced by and beyond the rolls, and also to serve as a backer for the blades of a rotary cutting element which has its axis of rotation above and longitudinally of the path of travel of the web. This element, during each pause of the web, is adapted and arranged to roll across the portion of the web imposed on the plate 23, thereby incising such portion longitudinally to form therein a row of parallel subdivisions corresponding with the dimensions of match splints, the alternate subdivisions being separated at their trailing ends from the body of the web, as indicated at *x*, Fig. 3. The cutting element in its preferred form embodies a roll 24 having a series of uniformly spaced peripheral cutters constituted by the outwardly projecting beveled edges 25 of rectilinear blades 26 which are mounted parallel to the axis of the roll in radial slots formed in the periphery of the roll. Each of the blades corresponds in length with that of a match splint and the space between adjacent blades corresponds with the width of a splint. One end of the roll has affixed thereto a cutting disk 27, the outer beveled edge of which is serrated to present a series of uniformly spaced cutting edges 29 in alternation with the spaces between the blades. The opposite end of the roll 24 has affixed thereto a gear wheel 30 hereinafter referred to, which, together with the disk 27, is conveniently secured to the body of the roll by means of through bolts 31. (See Fig. 6.)

The cutting element just described is rotatably mounted on a cross-bolt 32 between spaced depending lugs 33 formed on a reciprocative carriage constituted in the present instance by a slide 34 which overlies the path of the web and is movable transversely of the latter. The slide 34, which is mounted

in guide-ways in a suitable supporting frame 35 bridging the web, is operatively connected by means of a rod 36 with a crank disk 37 fast on the upper end of a vertical shaft 38 having its bearings in a bracket 39 which is bolted to one side of the table 22, whereby when the shaft 38 is rotated the slide is reciprocated transversely of the web. On the lower end of the shaft 38 is secured a bevel gear 40 in mesh with a similar gear 41 rotatably mounted on a stud-shaft 42 projecting from a bracket on the main frame, and to the hub of the gear 41 is fastened a ratchet 43 with which engages a pawl 44 pivoted on a disk 45 loosely mounted on the stud shaft 42. This disk is operatively connected by means of a rod 46 with the strap of an eccentric 47 fast on the shaft 11, the travel of which eccentric is such as to effect the advancement of the pawl disk 45 through an arc of ninety degrees, the pawl 44 thus engaging the ratchet 43 and correspondingly actuating the latter and its associated gear 41. Thence motion is transmitted through the gear 40 and its shaft 38 to the crank disk 37, thus reciprocating the slide 34 and the revoluble cutting element in timed relation to the intermittent travel of the web of match stock; that is to say, during one pause of the web the roll rotates across the web from one side to the other and in the next succeeding pause the roll rotates reversely across the web, and so on.

In each stroke of the slide 34 the peripheral blades of the revolving cutter roll consecutively engage the web and slit it longitudinally, the successive strokes being timed to provide uncut portions of the web in alternation with the rows of incisions, as indicated at *y*, Fig. 3. Coincidentally with the slitting of the web the trailing ends of the alternate subdivisions are severed by the disk cutter 27.

The ratio of the gearing for actuating the crank disk and the timing of the ratchet and pawl mechanisms for said gearing and for the feed rolls are such that during each dwell of said rolls the crank disk 37 makes a half rotation, which imparts to the slide 34 a stroke effective to produce a complete rotation of the cutter roll as it travels from one side to the other of the web. The crank disk remains at rest during the next succeeding rotation of the feed rolls, whereupon, while the feed rolls are at rest and in the next succeeding half rotation of the crank disk 37, a reverse stroke is imparted to the slide to effect the return rotative travel of the cutter roll across the web; and so on.

In order to ensure the proper registry or timing of the cutter roll at each side of the web, preparatory to the succeeding cross travel of the roll, the roll is equipped with the gear 30 previously mentioned, and at each side of the path of travel of the web is located

a rack 48 with which the gear meshes as and when the roll escapes the web. Hence in each stroke of the cutter roll, from one side to the other of the web, the cutting blades of the roll are positioned to engage and incise the web with precision. In the present instance the racks 48 are formed on or secured to one of a pair of horizontal guide plates 49 which are supported above and in spaced parallel relation to the backer plate 23, so as to overlie the web of stock, and are properly positioned to permit the free travel of the roll in engagement with the underlying web. These plates act as strippers to prevent the upward displacement of the web by the rotating cutters during the transverse travel of the roll.

A suitable friction device, for example, a spring pressed pin 50 (Figs. 5 and 6), is preferably slidably mounted in and transversely of the lug 33 adjacent the gear 30, so as to press against the opposing face of the latter. Thus, in case the machine should be run after the web has fully cleared the cutting roll, or in the absence of the web, the gear 30, together with the cutter roll, will hold its proper relative position until the gear has reached and engaged a lateral timing rack 48.

The incised portions of the web progress to and across the usual die members located adjacent the carrier 12, which members include vertically reciprocative inclined bars 51 which co-act with complementary fixed bars 52 so as to bear upon the alternate end-cut subdivisions of the web and bend or spread them from the normal plane of the web preparatory to the delivery of the leading or uncut end of the web to the carrier 12.

The bars 51 depend from a head 53 which is carried by a vertically reciprocative plunger 54 and has a suitably-disposed pendant knife 55 which, in the descent of the plunger, is adapted and arranged to sever the web across the uncut trailing ends of the longitudinally incised portions of the web after the leading end of the web has been inserted in the opposing strip holder of the carrier, thus producing a strip of match splints which is held by and advanced with the carrier, the next succeeding strip holder of the carrier being then presented to the immediately following portion of the web which has been acted upon by the cutting and spreading instrumentalities; and so on.

While I have illustrated the cutter roll as applied to a machine having co-acting die bars operative to spread the alternate subdivisions or splints produced in the web by the rotative action of the cutter roll, it is to be understood that any other suitable means for spreading such subdivisions may be employed. Indeed, in the broad aspect of my invention a spreading instrumentality may be omitted without departure from my invention, the characteristic feature of which resides in the provision of a revoluble cutter comprising a

series of peripheral rectilinear blades or knives parallel to an axis of rotation extending longitudinally of the path of the match stock, in combination with means for effecting relative co-operative movement between the cutter and the web transversely of the latter, whereby the individual blades or knives operate consecutively to incise the web in parallel longitudinal splint lines.

In prior constructions wherein a multiplicity of longitudinal incisions, transversely of the web, were produced by reciprocative bar dies, or by a multiplicity of simultaneously rotating circular blades having a common axis of rotation, the fibres in the body of the subdivisions were ruptured or distorted, whereas by the employment of a series of straight blades which consecutively act upon the web according to the principle of my invention, clean longitudinal incisions of the web are produced without appreciable distortion of the material between successive blades. It is also to be noted that in the case of a multiplicity of spaced-apart circular blades having a common axis of rotation, the lateral pressure of the subdivided material against the opposing blades, owing to the thickness of the latter, tends to bend the blades and to cramp and bind the interposed match stock.

I claim—

1. The combination with means for feeding sheet match stock, of a revoluble cutter having its axis of rotation longitudinally of the path of the stock and having a series of spaced-apart peripheral blades parallel to said axis, and means for effecting cooperative relative movement between the said cutter and the stock, transversely of the latter, whereby the blades operate consecutively to incise the stock in parallel longitudinal splint lines.

2. The combination with means for feeding sheet match stock, of a revoluble cutter having its axis of rotation longitudinally of the path of the stock and having a series of spaced-apart peripheral blades parallel to said axis, means for effecting cooperative relative movement between the said cutter and the stock, transversely of the latter, whereby the blades operate consecutively to incise the stock in parallel longitudinal splint lines, and means for timing the said cutter in relation to the stock.

3. The combination with means for feeding sheet match stock, of a carriage reciprocable transversely of the path of the stock, means for operating said carriage in timed relation to the travel of the stock, a revoluble cutter mounted on said carriage and having its axis of rotation longitudinally of the path of the stock, said cutter including a series of spaced-apart peripheral blades parallel to said axis, whereby during each stroke of the carriage the blades consecutively incise the stock in parallel longitudinal lines, and gear and rack

means operative to ensure the proper registry or timing of the cutter in relation to the stock.

4. The combination with means for feeding sheet match stock, of a revoluble cutter having its axis of rotation longitudinally of the path of the stock and having a series of spaced apart peripheral blades parallel to said axis, means for effecting cooperative relative movement between the said cutter and the stock, transversely of the latter, whereby the blades operate consecutively to incise the stock in parallel longitudinal splint lines, and means for transversely cutting one end of each alternate subdivision produced by the longitudinal incisions.

5. The combination with means for feeding sheet match stock, of a revoluble cutter having its axis of rotation longitudinally of the path of the stock and having a series of spaced apart peripheral blades parallel to said axis, means for effecting cooperative relative movement between the said cutter and the stock, transversely of the latter, whereby the blades operate consecutively to incise the stock in parallel longitudinal splint lines, and peripheral cutting members alternating with the spaces between said blades at one end of the latter, whereby one end of each alternate subdivision produced by the longitudinal incisions is severed from the stock.

6. The combination with means for feeding sheet match stock, of a revoluble cutter having its axis of rotation longitudinally of the path of the stock and having a series of spaced apart peripheral blades parallel to said axis, means for effecting cooperative relative movement between the said cutter and the stock, transversely of the latter, whereby the blades operate consecutively to incise the stock in parallel longitudinal splint lines, and a cutting disk fixed at one end of and rotatable with said revoluble cutter, the periphery of said disk being serrated to provide a series of cutting members in alternation with

the spaces between the said blades, whereby one end of each alternate subdivision produced by the longitudinal incisions is severed from the stock.

7. The combination with means for feeding sheet match stock, of a revoluble cutter having its axis of rotation longitudinally of the path of the stock and having a series of spaced apart peripheral blades parallel to said axis, means for effecting cooperative relative movement between the said cutter and the stock, transversely of the latter, whereby the blades operate consecutively to incise the stock in parallel longitudinal lines, means for transversely cutting one end of each alternate subdivision produced by the longitudinal incisions, and means for spreading or offsetting said alternate subdivisions.

8. The combination with a carrier for succeeding strips of match splints, and means for intermittently feeding sheet match stock toward and into engagement with the carrier, of a revoluble cutter having its axis of rotation longitudinally of the path of the stock and having a series of spaced apart peripheral blades parallel to said axis, means for effecting cooperative relative movement between the said cutter and the stock, transversely of the latter, whereby at regular intervals the blades operate consecutively to incise the stock in parallel longitudinal lines, means for transversely cutting one end of each alternate subdivision produced by the longitudinal incisions, means for spreading or offsetting the alternate subdivisions, and means for severing the stock across the trailing ends of the subdivisions adjacent the carrier after the leading end of the stock is engaged with said carrier.

Signed at Barberton, in the county of Summit and State of Ohio, this 7th day of September, A. D. 1927.

CHARLES F. WRIGHT.
